UNITED STATES PATENT OFFICE.

OLIVER B. REYNOLDS, OF BROCKTON, MASSACHUSETTS.

DUPLEX OSCILLATING PRINTING-MACHINE.

SPECIFICATION forming part of Letters Patent No. 362,998, dated May 17, 1887.

Application filed February 8, 1886. Serial No. 191,158. (No model.)

To all whom it may concern:

Be it known that I, OLIVER B. REYNOLDS, a citizen of the United States, residing at Brockton, in the county of Plymouth and State 5 of Massachusetts, have invented certain new and useful Improvements in Duplex Oscillating Printing-Machines, of which the following is a full, clear, and exact description, reference being had to the accompanying drawings, forming part of this specification, in which—

Figure 1 represents a side elevation of a printing-press embodying my improvements, and showing portions of the inking apparatus 15 removed from the left-hand side of the press. Fig. 2 represents in plan a mechanism for transferring the ink from the fountain to the inking-rollers. Fig. 3 represents in side elevation the mechanism illustrated in Fig. 2. 20 Fig. 4 is a plan view of the paper-carrying device. Fig. 5 is a side elevation, and Fig. 6 is a front view, of the same. Fig. 7 represents the stop for opening the nippers. Fig. 8 represents the adjustable frisket and connections. 25 Fig. 9 represents a view of a chase employed in my improved press. Fig. 10 represents a plan view of the paper-cutting mechanism. Fig. 11 is a side elevation of the same. Fig. 12 represents a plan view of the ink-fountain 30 and its operative mechanism. Fig. 13 represents a side elevation of the same.

My invention relates to a duplex printing-press designed to print separate sheets or to print from a web, either one or both, as desired; and my invention consists in the devices hereinafter described and specifically claimed.

To enable others skilled in the art to which my invention appertains, I will now describe 40 its construction and the manner in which I have carried it out.

In the said drawings, A represents the main frame, of any suitable form and construction and designed to sustain the working portions 45 of my machine. A transverse shaft, 2, journaled between the sides of the main frame, carries upon one end a suitable balance-wheel and driving-pulleys (not shown) and upon its opposite end a pinion, 3, which meshes with 50 a spur-gear, 4, mounted upon a transverse

shaft, 5, which carries on its end opposite the gear 4 a face-plate, 5', as shown in dotted lines in Fig. 1.

The spur-gear 4 and the face-plate 5' are provided with crank-pins 6, to which the inner ends of suitable connecting-links, 7, are pivotally attached, the outer ends of said links being secured to both sides of suitable swinging frames, B B, which carry the type-beds and inking apparatus. The construction and 55 operation of these swinging frames and their several connections will be hereinafter minutely described, in conjunction with certain other features with which they co-operate to produce the desired result.

The main frame of the machine is provided with any suitable means for attaching and securing two stationary platens, which are located upon two sides of said frame, and in such position that they receive the full impact of 7c the movable or oscillating type-beds, which alternately come in contact with the platens during the movement of the spur-gear 4 and face-plate 5' and the link-connection between these two features and the oscillating frames 75 B. This manner of attaching the frames B directly to each other is of importance, as the alternate movements of said frames are counterbalanced, thereby increasing the capacity 80 of the press and diminishing the noise and vibration incident to all presses when in operation.

Upon the lower portions of both sides of the frame A are secured brackets 6', to which are pivotally secured the lower ends of vertically-arranged arms 7', the upper ends of said arms being attached to a suitable frisket-frame, C, which consists, essentially, of a transverse rod, 8, having elongated slots 9 formed therein to receive and furnish the necessary means for 90 adjusting laterally the fingers e, which hold the sheet during the time the impression is being made. These fingers e not only have a lateral adjustment, but are slotted at 10, whereby said fingers are capable of vertical adjustment, 95 this compound adjustment being necessary to enable the press to print sheets of different size, as it permits the frisket-frame to be adjusted laterally and vertically to accommodate itself to the length and breadth of sheets to be 100

printed, or to regulate the fingers to the different widths of paper when printing from a web.

Suitable short arms, 12, secured to the shaft 5, have attached to them guides 13, which are affected by the movements of the paper-carrying device, and which are designed to permit the frisket to come squarely against the paper at the proper moment, or after the paper-carrying device has engaged the lower or cam-shaped end, 14, of the guides. It will thus be manifest that during the downward movement of the paper-carrying device, which is actuated in a manner I shall hereinafter describe, it permits the frisket-frame to be drawn 15 against the paper by the action of the springs 15, secured to the arms 7' and frame A, respectively. As soon as the impression has been made, the return movement of the paper-carrying device, by again engaging the cam-shaped portion 14 of the guides 13, forces said guide and frisket outward, the latter thereby releasing the paper and permitting the same to be deposited upon a table, as I shall herein-after describe. To better define this portion 20 of my improvements I will now describe the construction and operation of the paper-carrying device, and indicate a preferred mechanism for operating said device, whereby during 25 its reciprocating movement it automatically causes the frisket to engage and release the paper at stated intervals.

Within suitable journals on the main frame A is mounted a transverse shaft, 16, upon which 30 levers or walking-beams 17 on both inner sides of the frame A are centrally pivoted, as shown in Fig. 1. The outer ends of these beams 17 are provided with a series of holes, 18, to any one of which are attached the lower ends of 35 suitable yielding rods, which connect the walking-beams 17 directly with the paper-carrying device, whereby the latter is positively operated by the alternate movements of the former in a manner and for a purpose to be herein-after described. This connection between the paper-carrying device and the walking-beams is of peculiar construction, it being divided 40 into two parts, the lower portion, a, having a head, a', with a series of holes formed therein, 45 while the upper portion, b, which is attached to the paper-carrying device, is provided at its lower end with a yoke, d, as shown in Fig. 1. The lower portion, a, of this connection passes 50 through the yoke d, and carries upon its upper end a plate, e, which furnishes a bearing 55 for the upper end of a spring, f, coiled around the shank of the lower portion, a, of the connection, and between the plate e and lower face of the yoke f, thereby forming a yielding 60 connection, which is necessary, as the paper-carrying device will come in contact with a stop, 19, on the oscillating type-bed a short time before the walking-beams 17 have made 65 their full downward stroke, thereby relieving the paper-carrying device of the strain that would otherwise be brought upon it, as the adjustment between the lower portion of the

flexible connection and the walking-beams 17 cannot always be made with that minuteness that is desirable and necessary to the successful operation of the press. 70

As before stated, the upper portion of the connection between the walking-beams and paper-carrying device is attached directly to the latter, and is positively operated by the 75 movements of the former. Therefore, to give a steady and uniform motion to the walking-beams, I introduce between them and the driving mechanism a mechanism substantially as follows: 80

On the crank-pin 6, projecting from the spur-gear 4, I attach an arm, 20, the upper end of which is brought nearer the center of motion of said gear, thereby causing said arm to travel in a circle much smaller than the one the 85 crank-pin 6 itself would travel in, thereby decreasing the movement of the walking-beams with relation to the travel of the spur-gear 4 and its crank-pin. A rod, D, furnishes the necessary connection between the end of 90 the arm 20 and one of the walking-beams, and during the rotation of the spur-gear oscillates the walking-beams and causes the paper-carrying devices to travel up and down their guides-tracks D'' and operates the frisket-frame, for the purpose previously described. 95

The paper-carrying device is illustrated on an enlarged scale in Figs. 4, 5, and 6, and comprises two end pieces, 21, which furnish the necessary bearings for the working portions 100 of the same. Suitable anti-friction rollers, 22 and 23, are mounted between the side pieces, 21 and engage, respectively, the front and rear faces of the guide-tracks D'', and permit the paper-carrying devices to have a free movement up and down, they being guided by said tracks to operate, in their ascent or descent, the frisket, as before described. 105

A centrally-pivoted latching-lever, 24, is mounted upon one of the side pieces, 21, and is provided with projecting pins, 25 and 26, which engage stops and open and close the nippers in the following manner: During the descent of the paper-carrying device (it having previously taken hold of the sheet or web) 110 the roller 40' comes into engagement with the cams 14 and permits the springs 15 to draw the frisket against the paper, after which the paper-carrying device continues its downward movement, until its pin 25 comes in 115 contact with a latch, 27, pivoted to the lower end of an adjustable stop, 28, secured to the main frame of the machine, and causes said latch to yield, as shown in dotted lines, Fig. 7, to permit the said pin 25 to pass beneath it. As soon as the latter object is accomplished the walking-beams 17 come at rest, thereby leaving the pin 25 immediately beneath the pivoted latch 27. It is now evident, 120 as the walking-beams 17 begin their return (upward) motion, the pin 25 comes against the lower face, 27', of the pivoted latch, which has been returned to and held in its normal position by the spring 29 and stop-pin 30, and 125

this time causes the lever 24 to yield sufficiently to escape the lower face of the latch 27. It will be observed this movement of the lever 24 not only permits the paper-carrying device 5 to make its upward movement, or to return to its normal position, but it is designed to affect the position of the nippers 31 and 32, the former of which is pivoted and has on its inner face a cam, 33, having a notch, 32', with 10 which the inner end, 24', of the latch 24 is designed to come into engagement. Thus it is evident, as the lever 24 is being forced from its normal position by the action of the latch 27, the end 24' of the lever 24 is brought against 15 the cam 33 and forces the nipper 31 outward until the notch 32' is engaged by the arm 24', when it will be found the lever 24 is held in a locked position and the nippers 31 and 32 are open, in which position they remain, passing 20 upward to receive a fresh sheet of paper, or, if the operator is printing from a web, permitting the paper to pass between the nippers as the paper-carrying device is moving upward. In either case the nippers remain open until 25 the pin 26 on the lever 24 comes in contact with stops 34 or 35 at the upper end of frame A and near the top of the guide-tracks D'', as shown in Fig. 1.

If the operator wishes to print sheets, the 30 stop 35 is placed in the position shown in Fig. 1, and the paper-carrying device rides upon the curved upper end of the guide-tracks D'', in which position the nippers readily take the projecting edge of the sheet at the same moment the stop 35 engages the pin 26 and forces the end 24' of the lever 24 from its engagement with notch 32, and enables the nipper 31 to close upon the nipper 32 with sufficient friction to hold the interposed edge of the 35 sheet in position as it is being carried downward over the face of the platen, the closing of the nipper 31 being accomplished by a rod, 36, pivoted to said nipper and carrying a nut, 36', the said rod passing through a lug, 37, on 40 the side of the paper-carrying device, and a spring, 38, coiled around said rod, between the lug 37 and nut 36', whereby, when the nipper 31 is released, the spring draws the same against the nipper 32, as shown in Fig. 5, the 45 pivot lever 24 being also drawn to its normal position by the action of a spring, 39, and stop 40. In addition to the rollers 22 and 23, the paper-carrying device carries upon its sides small anti-friction rollers 40', which are 50 the rollers that operate against the face of the guides 13 to affect the position of the frisket.

The nippers 31 and 32 consist, essentially, of a curved and flat plate, respectively, and extend entirely across the platen. 55 Should the operator desire to print from a web, the same mechanism is employed, none of the several features being modified except the stop 34, which must then be thrown downward, as shown in Fig. 1, in which position it 60 releases the lever 24 from engagement with the nipper 31 and permits the nippers to take a new hold on the web and carry it downward

to be acted upon by the combined action of the movable type-form and stationary platen. In printing either from the web or from individual sheets it is necessary to stop the paper-carrying device just prior to the moment the type-form comes against the platen. Therefore, in addition to the stops 19, some means must be adopted to limit the upward-and downward-movement of the paper-carrying device when printing from a web, and when it is desired to vary the size of sheet to be printed and to limit the downward movement only when individual sheets are being 70 printed; it being evident the said paper-carrying device must make its full upward stroke in this instance, as the said device should practically advance high enough upon the curved portion of the guide-tracks D'' to readily take 75 hold of the edge of the sheet. Therefore, to meet these several requirements, I form the series of holes in the ends of the walking-beams 17 and flexible connection, so that by changing the lower end of the said connection from 80 one point to another I increase or diminish the length of travel of said carriage. Thus, for example, if a very small sheet is required I connect the lower hole in said connection with the hole near the pivoted center of the 85 walking-beam. This gives a shorter downward movement, and therefore less travel to the paper-carriage, and by reason of the duplex construction of the press I am at liberty to make one paper-carriage make a short movement and yet permit the opposite one, by making the connection at the extreme end of the beam 17, to make its full movement, and thereby print a much larger sheet at the same time the small sheet or web is being printed. Thus I am 90 enabled to construct a press which is capable of printing two jobs of different sizes (and colors, if desired) at the same time, the movements of one portion of the machine not conflicting with the opposite movements of the opposite 95 portion, but, instead, serving as a counter-balance for the same and producing a compact substantial double-acting press designed to print from two webs at one time two separate sheets at one time, or to print alternately 100 from a web at one side and separate sheets at the opposite side, the paper in either case being 105 automatically received and released.

I will now describe the inking-rollers and the mechanism for transferring the ink from 110 the fountain to the rollers, these several features being duplicated on opposite sides of the machine, although I have shown the inking apparatus on but one side.

The movable type beds H H are constructed 115 with rearward extensions. Upon one of each the inking-rollers 41 are designed to pass during the oscillating movement of the swinging frames B. The inking-rollers 41 are attached to a pivoted frame, 42, (see Figs. 1, 2, and 3,) 120 and are operated by suitable connecting-rods, L, attached to said pivoted frames on opposite sides, the lower ends of these rods L being loosely connected to the outer ends of levers 125

or walking-beams M, pivoted at their centers to the main frame, as shown in Fig. 1, and operated to cause the inking-rollers to pass over the face of the type-form and to come at 5 rest on a large ink-roller, to be hereinafter described.

Upon the main drive-shaft 2 is secured a pinion, l, which meshes with a gear-wheel, m, on a transverse shaft, n, said shaft carrying on 10 its opposite end a pinion, o, which meshes with and communicates its motion to a gear-wheel, p, on a transverse shaft, r. A crank-arm, s, on the shaft r has attached to its outer end the upper end of a connecting-rod, N, whose lower 15 end is attached to the walking-beam M at a point between the outer end of said beam and its center of motion. From this construction it is clearly manifest the rotation of the drive-shaft and the pinions 3 and l alternately oscillates the swinging frames B B, which carry 20 the type-forms, and also operate the inking-rollers to pass over the face of the type in one direction during each of the oscillating movements of said frames.

25 I will now describe a preferred form of mechanism for causing the rollers which take the ink from the fountain and the inking-rollers 41 to approach each other, whereby the latter rollers receive from the former at each oscillation of the press an amount of ink sufficient 30 to supply the type for the ensuing impression, the several mechanisms employed to carry out the feature being arranged to travel a distance sufficient to cause the two series of rollers to 35 meet at a point near the outer ends of the extensions h of the type-beds. Upon shafts 43, which furnish the necessary bearings for the pivoted ink-roller frame 42, is mounted a segmental gear, 44, which is designed to engage a 40 pinion, 45, on a shaft, 46, running parallel with the said shaft 43. On the shaft 46 are rigidly mounted arms 47 47', which project outwardly and furnish the necessary means for sustaining a large roller, 48, which is mounted to 45 revolve on a shaft, 49, having on one end a pinion, 50, which meshes with the teeth on a large stationary rack, 51, mounted on a boss, 52, projecting from an extension, 53, of the swinging frames B, as shown in Figs. 1, 2, and 3.

50 The inner periphery of the roller 48 is provided with oppositely-arranged ratchets 53 and 54, and the shaft 49 is provided with a sleeve, 55, having sockets 56 and 57, (see dotted lines, Fig. 2,) in which are mounted spring- 55 actuated plungers 58 and 59, which are designed to engage the ratchets 53 and 54 to rotate the roller 48. It will now be manifest the movement of the walking-beams M operates the pivoted ink-roller frame 42, and this 60 frame, being rigid on the shaft 43, operates the segment 44, which in turn rotates the pinion 45. The arms 47 47' being rigid on the shaft 46, it is evident said arms must describe the arc of a circle, and in making this movement 65 they carry with them the roller 48. While this portion of the mechanism is making its movement, the inking-rollers 41 and frame 42

are also making a similar motion, and just before the press has made its full stroke it will be found these rollers 41 and 48 have 70 come together in the position shown in dotted lines, Fig. 3, in which position they remain until the press begins its return-stroke, when the different series of rollers move away from each other and come together again at the 75 completion of its next stroke at a point almost if not quite diametrically opposite the place they last came together. Thus, for instance, if the rollers meet at the position shown by dotted lines in Fig. 3 at one of the 80 oscillating movements of the press, its next position will be at a point at or near the extreme outer end of the lower extension, h, of the type-bed, where it again transfers the ink to the rollers 41. By this means a systematic 85 and even amount of ink is distributed to the rollers 41, and the impressions will therefore be of a uniform appearance.

It has been found by actual experience that after repeated use the ink will form ridges or 90 creases on the face of the roller 48 at the points where the rollers 41 come against the face of said roller 48. Therefore, to obviate this difficulty, and to keep the face of the roller 48 smooth and free from ridges or other irregularities, I impart to said roller during its movement a motion transverse to its rotation. This enables the roller 48 to present all portions of its face to the action of the rollers 41, and it necessarily gives more desirable effects 95 in the production of uniform impressions than would occur if this transverse movement was not given to said roller. To accomplish this important result I construct the roller 48 with a projecting flanged hub, 60, upon which is 100 placed a loose collar, 61, through which pass pins 62, that have attached to their outer portions the bifurcated ends of a lever, 64, pivoted to a lug, 65, projecting from the arm 47. The opposite end of the lever 64 passes through 105 a slot, 66, in said arm, and carries on its extreme outer end a small anti-friction roller, 67, which is designed to ride upon the inclined face of a fixed cam, 68, on one side of the extension 53 of the frames B during the 110 rotation of the shaft 46. Thus it will be seen as the shaft 46 rotates and carries the arms 47 and roller 48 upward, the said roller 67, acting on the cam 68, operates the lever 64 and imparts to said roller 48 a sliding movement 115 transverse to its rotation. As the lever 64 is forced from its position laterally, I introduce between said lever and a hook, 69, on the arm 47 a spring, 70, which always keeps said roller against the face of the cam.

120 In addition to the features enumerated above, and to bring every possible portion of the face of the roller 48 to the action of rollers 41, I employ another mechanism, which is automatic in its movement and is designed to 125 check the rotation of said roller in one of its movements. This mechanism is as follows: An arm, 71, extends vertically above the rack 51 and carries at its top an adjustable cam,

72, and the plunger 56 has projecting from its side and through a slot in the socket a pin, 73, which comes in contact with the cam 72 and temporarily releases said plunger 56 from its engagement with its ratchet 53 and stops the rotation of the roll 48. The rotation of the shaft 49 is so "timed," however, that the pin fails to engage the cam on the forward movement of the roll 48 toward the rollers 41; but 5 after the said roll has moved a short distance on its return from the rollers 41 (see dotted position, Fig. 3) the pin meets the rounded face of the cam 72 and withdraws the plunger from its ratchet. The rotation of the roller 15 48 will now cease, as the opposite pawl or plunger, 57, simply slips by its ratchet 54. Therefore when the pin 73 escapes by the cam 72 the position of the roll 48 will have been changed with relation to the shaft, and when 20 brought to the action of the roller 41 again a new portion of said roll will be presented.

Bearing with slight friction against the periphery of the roller 48, and in front of the same, are the small rollers 74, mounted in arms 25 75, pivoted on bosses 76, projecting inwardly from the arms 47, and held together by springs 77, as shown in Figs. 2 and 3, these rollers serving to distribute the ink over the face of the roller 48.

30 The fountain 78, from whence the roller 48 receives its ink, is of ordinary construction, except that it has a roll, 79, mounted on a shaft, 80, from whence depends a slotted arm, 81, which is attached to the slotted end of a 35 rod, 81', projecting from the main frame A and carrying an adjustable stop, 82, the purpose of which will be hereinafter fully described. A suitable bracket, P', projecting from the swinging frame B, supports the ink - fountain 78, and also furnishes a bearing for a 40 transverse shaft, 83, on which is mounted, on each end, two upwardly-extending arms, 84 and 85, the former of which is rigid on the shaft 83, while the latter is loosely mounted 45 thereon, the two arms being connected by springs a'' and the arms 84 being connected to the fountain by springs b', as shown in Figs. 12 and 13. On the shaft 83 and outside of the arms 84 is attached a bell-crank lever, 86, the 50 lower arm of which carries an adjustable weight, c', which keeps said arm against a stop, d', projecting from the shaft 83, as shown in Fig. 13.

55 From this description of these parts it is manifest the oscillating motions of the swinging frame B, which carries the ink-fountain and connections, causes said devices to move forward until the upper arm, e', of the bell-crank lever 86 comes against the adjusted 60 stop 82 on the rod 81'. The forward movement of the frame B and connections will now force the lower arm of said lever from its stop d', when the spring b' will draw the rollers g' g''' against the roller 79. At the same time the 65 pin f', which connects the arm 81 with the rod 81', will travel the length of the slot in the rod, when the rod, through the agency of a suitable

pawl and ratchet, h', will rotate the roller 79 and present a new surface to the action of the rolls g' g'''. On the return movement of the 70 frame B the stop 82 is released from its engagement with the arm e', and the weight c' permits the bell-crank lever 86 and rolls g' and g''' to assume the position shown in Fig. 13, while a spring, k', draws the arm 81 to its 75 normal position, as therein shown.

There are times when it will be desirable to keep the roll g' against the face of the roller 48 a longer time than is ordinarily desired, as more ink may be needed at some times than at 80 others. To accomplish this feature I secure to the arm 84 a latch, l', which is adjusted against a stop-pin on the fountain 78. I am enabled, therefore, to so regulate the travel of the rolls g' and g''' that the former roll may only touch 85 the face of the roll 48, or may bear against the face of said roll a short period after it has commenced its travel toward the inking-rollers 41.

In conjunction with the adjustable stops 19 90 on the movable type-beds, which, as before stated, are designed to check the downward movement of the paper-carriage, I employ suitable chases, P, of a construction substantially as shown in Fig. 9, wherein the chase is 95 illustrated as having a thin curved plate projecting from its lower end. The said plate is formed of finely-tempered spring metal, and is bolted or otherwise secured to the chase. The lower end of the plate rests against the 100 base of the type-bed, and being curved necessarily throws the upper portion of the chase outward when the chase is first inserted. Then the operator forces the upper end of said chase back to its seat against the type-bed, and 105 locks it rigidly in this position by any suitable means, thereby insuring the firm bearing of the chase against the type-beds. This manner of locking the chase is not shown, as any well-known mechanism may be employed; but 110 the construction of the chase is clearly set forth in the figure before mentioned.

The press as now described is a duplex press, and is adapted to print two different impressions during each of the oscillating 115 movements of the press. Thus I am enabled to print separate sheets or print from webs. If the operator desires to print from a web, he must employ some means for holding the web so that it will feed regularly, and also adopt a 120 suitable mechanism for severing the web after the impression is made. These important features I have accomplished, and the mechanism to be hereinafter described are designed to be a portion of the press, although they 125 may be removed to change the web to individual sheet-printing.

In Fig. 1 I have illustrated a press, showing a web upon one side, while the opposite side is designed for separate sheets. Therefore on 130 the side on which the web is located I have mounted the web-holding and paper-cutting devices, it being manifest I may remove these mechanisms and use both sides of the press for

sheet-printing, or may attach to the side which is shown as adapted for sheet-printing web-holding and paper-cutting mechanisms corresponding to those on the opposite side. To 5 accomplish these several results I attach to the top of the frame A a double-inclined bracket or shelf, Q, upon which the web-holding devices are secured and which may form the feeding-table for separate sheets when 10 used for that purpose. Upon this bracket is removably secured a frame, R, in the top of which a shaft, r' , carrying the web S, is mounted. The frame R has a projecting arm, which furnishes the fulcrum for a suitable lever, T, the lower arm of which has adjustably secured thereto the upper end of a rod, U, whose lower end is attached to the pin on which the end of one of the links 7 is attached. The upper end of the lever T is slotted and 20 carries a weighted depending pawl, V, which is adjusted on the lever by means of a hand-screw, s' , passing through lugs t' on the lever and upper portion of the pawl.

On one end of the shaft r' is mounted a 25 ratchet-wheel, u , and a pulley, w , over the face of which is passed a strap, x , having a weight attached thereto, to prevent a too rapid feed of the paper. In addition to the pulley w , the shaft r' carries a pulley, y , that 30 is engaged by a curved portion, T' , on the lever T, and serves as a brake for determining the rotation of the web. From the arrangement of these parts it is manifest the movement of the frame B toward the platen 35 carries with it the rod U, which, being attached to the lower arm of the lever T, forces the upper end of said lever T and adjustable pawl V downward, and until the curved portion T' of said lever comes against the periphery of the 40 pulley y , and thereby stops the unwinding of the web, this movement occurring just prior to the moment the impression is made. As the frame B moves away from the platen the rod U draws upon the lower end of the lever T, 45 and raises the upper end of said lever away from its contact with the periphery of the pulley y . At the same time the notched end of the pawl V comes in contact with the ratchet-wheel u and imparts to the web S a rotary 50 motion, thereby unwinding said web, the amount of feed being accomplished by the adjustment of the pawl V and suitable devices beneath the web, which take up the surplus slack, thus always permitting the web to be 55 held with sufficient tension to keep the paper in condition to be successfully operated upon by the paper-carriage.

Beneath the web S, and mounted between the sides of the frame R, are suitable devices 60 to regulate the tension of the web as it leaves the roll. These devices consist, essentially, of the small rollers a'' and e'' , the latter being mounted in a weighted lever, d'' , fulcrumed at b'' on the frame R. Other rollers, e'' and g'' , 65 (the former is mounted in a weighted lever, h'' , and the latter in a small bracket projecting from the platen-frame,) constitute the ten-

sion device, the web in its delivery from the roll passing under the roller a'' , thence over roller e'' , and finally between the roller e'' and g'' , after which it passes over the face of the platen and between the nippers 31 and 32 of paper-carrying devices. 70

After the impression has been made, the web is drawn downward by the nippers taking hold the paper again at or near the top of the platen-frame, and is subjected to the action of a suitable cutting apparatus, which severs the web and deposits the sheets upon a table suitably placed beneath the cutting apparatus. 80

The cutting mechanism is illustrated on an enlarged scale in Figs. 10 and 11, and comprises a plate, A', which is bolted or otherwise secured to the inside of the main frame A, and is provided with a channel or guide, B', 85 in which are adjusted vertically arms C', that have attached to them a knife or cutter, D'. Screws E', operated by a hand-wheel, F', and miter-gears G'G', pass through lugs on the back of the arms C' and adjust said arms to correspond with the size of sheet to be severed. 90

The arms C' are also provided with grooves H', in which slides the reciprocating plate I, having a knife or cutter, I', secured thereon, the said plate having extending ends i'' , that 95 are perforated to receive the ends of rods k'' , which project from lugs l'' on the side of the arms C'. Between the lugs l'' and ends i'' and around the rods k'' are placed springs m'' , which retract the knife or cutter I' after the 100 paper has been severed. The lower ends of the arms C' have fulcrumed therein a lever, K', provided with arms n' , which pass through openings o' in the plate I, and the lower arm of said lever K' has pivoted thereto a pawl, 105 L', which is engaged and operated by a catch, M', on the swinging frame B. This catch is made adjustable on the frame B, to correspond with the adjustment of the arms C', and is designed to engage the pawl during the movement of the frame B. Thus, as the frame B, 110 which, as before described, carries the type-form, moves forward, it carries with it the catch M', which engages but rides past the notched end of the pawl L'. On the return of the frame, 115 and after the impression has been made, the notched portion of the catch engages the notched end of the pawl and draws upon said pawl. This action operates the lever K' and forces the plate I, carrying the cutter I', inward, 120 thereby severing a portion of the web. The continued outward movement of the frame causes the catch to disengage itself from the pawl, when the latter is returned to its normal position by the spring N' and stop O', and 125 is in condition to be operated upon again during the succeeding movements of the frame. I am thus enabled to automatically sever the web and to adjust the cutting apparatus to correspond to the size of sheet to be printed. 130

I do not broadly claim in this application a chase having a thin extension at its lower end, as such construction is contained in my other application, Serial No. 185,809, but limit my-

self to a chase having a curved thin extension of springy metal, as described.

Having thus described my invention, what I claim as new, and desire to secure by Letters 5 Patent, is—

1. A printing-press having duplex oscillating type-forms adapted to make alternate impressions during the oscillation of the press, substantially as herein described.
- 10 2. A duplex printing-press provided with two oscillating type-forms adapted to print alternately individual sheets and a web in each direction of their movement, substantially as herein described.
- 15 3. In a printing-press, the frame A, having a stationary platen upon two sides of its transverse center, in combination with oscillating type-forms operating alternately to print in the forward direction of their oscillation, substantially as herein described.
- 20 4. In a printing-press, a frame provided with stationary platens upon two sides of its transverse center, in combination with counterbalanced oscillating type-forms adapted to engage the platens and make alternate impressions in the forward movement of their oscillation, substantially as herein described.
- 25 5. In a printing-press, a main frame having a stationary platen upon two sides of its transverse center, in combination with frames B on opposite sides of the main frame, a main drive-shaft with pinion thereon, a transverse shaft, 5, a spur-gear and face-plate upon said shaft, and a link-connection between the said 30 gear and face-plate and the upper end of the frames, whereby the frames are counterbalanced and are adapted to print in the forward movement of their oscillation, substantially as herein described.
- 35 6. A printing-press having guide-tracks D'', in combination with a reciprocating paper-carriage engaging said tracks and having nippers adapted to automatically open and close to permit the passage of the paper between 40 them, substantially as herein described.
- 45 7. The combination, with a printing-press, of an alternately-reciprocating paper-carriage, operating in vertical planes upon two sides of said press, substantially as and for the purpose described.
- 50 8. In a printing-press, the automatically-reciprocating paper-carriage, in combination with a frisket operated by the vertical movement of the same, substantially as described.
- 55 9. In a printing-press, the reciprocating paper-carriages arranged upon two sides of the press and moving in opposite directions, in combination with friskets engaged and operated by the travel of said carriages, substantially as described.
- 60 10. In a printing-press, the frame A, having the platens secured upon two sides of its transverse center, in combination with guide-tracks D'' upon the platen-frame, suitable paper-carrying devices, substantially as set forth, operated by the movements of the press to reciprocate upon the guides, and mechanism,

substantially as described, for reciprocating said devices, substantially as herein set forth.

11. In a printing-press, a main frame provided with stationary platens and the guide-tracks upon the platen-frames, in combination with reciprocating paper-carrying devices, substantially as set forth, operated by the movements of the press, a frisket operated by said devices, and the guides 13, having cams 14, whereby the position of the frisket is changed, substantially as herein described.

12. In a printing-press, the combination, with a main frame having platens thereon and automatically reciprocating paper-carrying devices, substantially as described, of a frisket comprising the transverse shaft 8, the guides 13, having cams 14, the fingers c, and the spring-actuated arms 7', secured to the main frame, and shaft 8, whereby, when the paper-carriage engages the cams 14, the frisket is drawn to or forced from its engagement with the platens, substantially as and for the purpose herein described.

13. In a printing-press, a paper-carriage having the roller 40', in combination with a frisket comprising the slotted shaft 8, the vertically-arranged slotted fingers c, adjustably secured to the shaft, and the guides 13, having cams 14, substantially as and for the purpose set forth.

14. A printing-press having the guide-tracks D'' and a reciprocating paper carriage, substantially as described, engaging said tracks and automatically operated by the movements of the press, in combination with adjustable stops at the upper and lower ends of the guide-tracks, adapted to engage a lever on the carriage to open and close the nippers of said carriage and to permit the passage of the paper, substantially as herein described.

15. In a printing-press, a main frame having platens thereon, in combination with vertically-reciprocating paper-carrying devices, substantially as described, adjustable stops at or near the base of the platens to open and lock the nippers of said carriage, and suitable stops or cams at or near the upper portion of the platens adapted to release and close said nippers, substantially as herein described.

16. In a printing-press, the main frame having platens secured thereto, in combination with an adjustable stop, 28, a pivoted yielding latch, 27, mounted thereon near the base of the platens, an adjustable stop, 34 or 35, located near the top of the platens, and a paper-carrying device, substantially as described, having a lever with pins projecting therefrom, whereby the paper-carrying device, at the beginning of its upward reciprocation, engages the latch 27 to open the nippers of said device, and at the completion of said reciprocation engages the stop 34 or 35 to close said nippers, substantially as herein described.

17. In a printing-press, the main frame, the stop 28, adjustably secured thereto and provided with a pivoted latch, 27, a retracting-spring, 29, and pin 30, in combination with a

paper-carrying device, substantially as described, having a lever with pins projecting therefrom and a movable nipper, whereby the said nipper is forced outward and held in an open condition by the latches and levers and the paper permitted to pass between the nippers during the upward movement of the paper-carriage, substantially as herein described.

18. In a printing-press, a connection, substantially as described, between the paper-carriage and the driving mechanism, whereby the travel of the carriage varies with relation to the size of sheets, in combination with said carriage and the adjustable stops on the type-bed for arresting the downward movement of the same, substantially as herein described.

19. In a printing press, the main frame and adjustable stops secured thereon and a reciprocating paper-carriage, in combination with a yielding connection, substantially as described, between the paper-carriage and its driving mechanism, whereby the latter completes its stroke without affecting the position of the former, substantially as and for the purpose herein described.

20. In a duplex printing-press, a main frame having platens secured thereto and suitable reciprocating paper-carriages upon two sides of the frame, in combination with a flexible adjustable connection, substantially as described, between said carriages and their driving mechanism, whereby the connection at one side of the press may be adjusted to increase or diminish the downward travel of one of the carriages without affecting the travel of the opposite carriage, substantially as herein described.

21. In a printing-press, a mechanism for causing the paper-carriage to regulate its travel to correspond to varying size of sheets, comprising the walking-beams or levers 17, journaled between the sides of the frame, mechanism for operating the walking-beam, and a connection, substantially as described, between the said beam and carriage, whereby the connection may be adjusted on the walking-beam to increase or diminish the downward travel of the carriage, substantially as herein described.

22. In a printing-press, a mechanism for adjusting the travel of the paper-carriage to correspond to the size of sheet, comprising the walking-beams or levers 17, journaled in the main frame and provided with a series of adjusting-holes, 18, and mechanism connected with the main driving-shaft for oscillating the beam, in combination with a two part connecting-rod, *a b*, attached to the beam and paper-carriage, a series of adjusting-holes in the lower portion of the connection, whereby the beam and connecting-rod are adjusted on each other, a plate, *e*, on the upper portion and a yoke, *d*, on the lower portion of the rod *a b*, respectively, and a spring between the plate and yoke, whereby a yielding connection is

formed, substantially as and for the purpose described.

23. In a printing-press, a main frame having platens secured thereon, in combination with reciprocating paper-carrying carriages, the walking-beams or levers mounted to oscillate within the frame, a drive-shaft having a pinion, 3, a spur-gear, 4, having a crank-pin, an arm, 20, projecting therefrom, a rod connecting the arm with the walking-beam, and a flexible connection adjustably secured to the walking-beam to change the downward stroke of the carriage, substantially as herein described.

24. In a printing-press, the combination, with a suitably-arranged platen and an adjustable stop secured to the type-bed, of a chase provided with a curved thin extension and a reciprocating paper-carrying device automatically adjusted to come at rest at the base of the main portion of the chase, whereby sheets of different size may be printed, substantially as herein described.

25. A chase for printing-presses, provided with a curved tempered extension secured to the lower portion of the chase, substantially as herein described.

26. In a printing-press, a main frame having a platen secured thereon and a suitable oscillating frame carrying the type bed, in combination with a reciprocating paper-carriage, provided with guide-rollers 22 and 23, a stationary and movable nipper, a pivoted lever on the side of the carriage, and an adjustable stop on the main frame for engaging the lever to open the nippers, substantially as herein described.

27. A paper-carriage for printing-presses, consisting of the side pieces, 21, the guide-rollers 22 and 23, a stationary nipper, 32, a nipper, 31, pivoted to the side pieces, 21, a notched cam upon said nipper, a pivoted lever, 24, having pins 25 and 26 projecting therefrom, a spring for drawing the lever to its normal position when released from the notched cam, and a spring and rod for closing the nipper 31 when said lever is released, substantially as herein described.

28. A reciprocating paper-carriage for printing-presses, comprising a frame with guide-rollers mounted therein, which engage guides on the sides of the platen-frame, a stationary and movable nipper consisting of a straight and curved plate, between which the paper passes during the upward movement of the carriage, a lever and stop for opening the nippers, and a stop, 34 or 35, at the top of the platen-frame for closing the nippers at the completion of the upward movement of the carriage, and a guide-roller, 40', substantially as herein described.

29. In a printing-press, the inking-rollers 41 and a roller, 48, in combination with mechanism comprising the gears 44 and 45, whereby the said rollers 41 and 48 describe arcs of circles and come together at or near the rear ex-

- tended portion of the type-bed, substantially as herein described.
30. In a printing-press, the inking-rollers 41, secured to a pivotal frame and adapted to pass over the face of the type and come at rest alternately above and below the type-bed and to the rear of the same, in combination with a transfer-roller, 48, adapted to describe alternate arcs of circles in two directions to cause said roller 48 to come in contact with the rollers 41, whereby the ink is transferred from the roller 48 to the rollers 41 at each oscillation of the press, substantially as herein described.
- 15 31. In a printing-press, the pivoted inking-roller frames operated by the oscillations of the press, and the inking-rollers 41, attached thereto, in combination with a segment, 44, a pinion, 45, the parallel shafts 43 and 46, the arms 47, rigidly secured on the shaft 46, and a roller, 48, carried by the arms 47 and operated by the pivoted frame, and driving mechanism to cause the said arms 47 and roller 48 to move forward in curved lines and come at rest at the upper and lower portions of the type-frame and to the rear of the same, whereby it meets and transfers its ink to the rollers 41 at each oscillation of the press, substantially as herein described.
- 20 32. In a printing-press, the pivoted ink-roller frame, the rollers 41, attached thereto, and mechanism for operating the pivoted frames, in combination with the segment 44, a pinion, 45, engaged thereby, the shafts 43 and 46, the arms 47, rigidly attached to the shaft 46, a shaft, 49, mounted in the outer ends of the arms, and a loosely-mounted ink-roller, 48, carried by said shaft to move forward in curved lines toward the type-beds to transfer the ink 25 to the rollers 41, substantially as and for the purpose herein described.
- 30 33. In a duplex printing-press, a main frame having stationary platens thereon and the oscillating frames B, provided with type-beds, in combination with the pivoted ink-roller frames, the inking-rollers 41, attached thereto, a roller, 48, supported near the ink-fountain, and mechanism, substantially as described, for moving the rollers 41 and 48 synchronously 35 in curved lines forward and rearward, substantially as and for the purpose herein described.
- 35 34. In a printing-press, the pivoted ink-roller frames, the rollers attached thereto, suitable driving mechanism, the roller 48, loosely mounted on its shaft, connections, substantially as described, between the roller-frames and rollers 48, and a mechanism, substantially as set forth, for imparting a transverse motion 40 to the roller during its curvilinear movements, substantially as herein described.
- 40 35. In a printing-press, the oscillating frames B, the driving mechanism, the arms 47 47', attached to the frames, the roller 48, suitable mechanism between the frames and the roller to cause the latter to move in curved lines forward and rearward, a collar loosely arranged
- on the hub of the roller, a lever fulcrumed upon the arms 47, suitable pins, 62, on the collar, with which one end of the levers is attached, an anti-friction roller, 67, on the opposite end of the lever, a cam, 68, upon the frame B, and a spring for keeping the roller 67 against the face of the cam, whereby the roller 48 is moved transversely upon its shaft, substantially as herein described.
- 45 36. In a printing-press, the combination, with the roller 48 and its operative mechanism, as set forth, of the distributing-rolls 74, the arms 75, pivoted to the arms 47 47', and springs 80 for keeping the rolls against the periphery of the roller 48, substantially as herein described.
- 50 37. In a printing-press, the oscillating frames B, the arms 47, and gearing interposed between the frames and arms for moving the latter in curved lines, a roller, 48, having oppositely-arranged ratchets 53 and 54, a shaft, 49, upon which the roller is mounted, a pinion on said shaft, a stationary rack, 51, secured to the oscillating frames B, and oppositely-located 55 spring-pawls 58 and 59, adapted to engage the ratchets to rotate the roller during its curvilinear movement, substantially as herein described.
- 55 38. In a printing-press, the roller 48 and mechanism for moving said roller in curved lines, in combination with a vertical arm, 71, a cam, 72, adjustably secured thereon, a sleeve, 55, on the roller-shaft, suitable sockets in the sleeve, spring-actuated pawls adapted to engage oppositely-arranged ratchets on the inner periphery of the roller, and a pin projecting from one of the pawls, whereby, when said pin engages the cam 72 on the return movement of the arms 47, the pawl 59 is withdrawn 60 and the rotation of the roller 48 temporarily checked, substantially as and for the purpose described.
- 60 39. In a printing-press, the oscillating frames, the ink-roller frames pivoted thereto, walking-beams or levers M, operated by power derived from the drive-shaft, and the rods L, connecting the ends of the walking-beam with the ink-roller frames, substantially as herein described.
- 65 40. In a printing-press, the oscillating frames and their driving mechanism, in combination with brackets P, projecting from said frames, an ink-fountain, 78, supported on the outer ends of the bracket, a roller, 79, on a shaft, 80, journaled in the fountain, an arm, 81, depending from the shaft, a stationary rod, 81', on the main frame, and a suitable pawl and ratchet whereby the oscillations of the frames B cause the arms 81 to engage the rod 81', to rotate 70 the roller 79, substantially as herein described.
- 70 41. In a printing-press, a main frame having a slotted arm, 81', projecting therefrom, the oscillating frames B, provided with brackets P, an ink-fountain supported on the bracket, a 75 shaft journaled within the frame of the fountain and having a roller, 79, a slotted arm, 81, depending from the shaft and engaging the slotted portion of the rod 81', an adjustable

stop, 82, on said rod, the arms 84 and 85, carrying the rollers g' and g'' , and a weighted bell-crank lever with which the stop 82 engages, whereby the oscillating movements of the frames B rotate the roller 79 and trip the bell-crank lever to bring the rolls g' and g'' against the periphery of the roller 79, substantially as herein described.

42. In a printing-press, the main frame, the rod 81', projecting therefrom and having an adjustable stop, 82, the oscillating frames B, the brackets secured thereto, the ink-fountain, roller, and shaft, the arms 81, 84, and 85, the rolls g' and g'' , a weighted bell-crank lever mounted on a shaft which carries a stop, d' , the roller 48, the springs for drawing the rollers g' and g'' together and against the roller 79, and an adjustable latch, l' , whereby the length of time the roller g' remains against the periphery of the roller 48 may be determined, substantially as and for the purpose set forth.

43. In a printing-press, the oscillating frames B, in combination with a mechanism comprising the lever T, operated by the movements of said frames, adapted to regulate the feed of the paper and to temporarily stop the feed while the impression is being made, substantially as described.

44. In a printing-press, the main frame, the oscillating frame B, and the driving mechanism, in combination with a double-inclined shelf, Q, a frame, R, detachably secured to the shelf, a shaft in the upper portion of said frame, a pulley, y , mounted thereon, a lever, T, fulcrumed on the frame R, and a rod, U, attached to the lever and oscillating frame, whereby the oscillations of said frame operate the lever to check the feed of the web, substantially as herein described.

45. In a printing-press, the main frame, the frame R, supported thereon, the oscillating frame B, and the connecting-rod U, in combination with a shaft, r' , in the top, and a lever, T, on the side of the frame R, a depending pawl adjustably secured on the upper portion of the lever, a ratchet-wheel, u , and the pulleys w and y , substantially as herein described.

46. In a printing-press, a web-holding mechanism adjustably secured to the main frame of the press, and comprising a frame, R, between the sides of which the web is mounted, a lever fulcrumed on the frame and having a curved portion, T', a depending pawl, and mechanism,

as described, for adjusting the pawl, a ratchet-wheel on the web-holding shaft, toward which the pawl is adjusted, and a pulley, y , whereby when the lower arm of said lever is thrown upward the curved portion T' of the lever bears against the pulley y and stops the unwinding 60 of the web, and when said arm is drawn downward the pulley is released and the pawl V engages the teeth of the ratchet and rotates the web, substantially as herein described.

47. In a printing-press, a main frame and a 65 web-holding mechanism, substantially as described, supported upon said frame, in combination with the oscillating frames B, a connecting-rod for operating the web-feeding devices, and a tension device comprising the 70 rollers and adjustable weighted levers between the web and main frame, whereby the tension of the web is regulated, substantially as herein described.

48. In a printing-press, the main frame A and the oscillating frames B, in combination with a 75 paper-cutting mechanism comprising grooved plates A' upon the inside of the main frame, the arms C', vertically adjusted by means of screws and gears, a knife or cutter secured to 80 the arms C', a plate, I, carrying a cutter or knife, I', and sliding within said arms, springs for retracting said plate and cutter, and a tripping mechanism operated by the oscillations of the frames B to move the plate and cutter 85 I I' to sever the web, substantially as herein described.

49. In a printing-press, the main frame, the adjustable arms C, having a cutter or blade attached thereto, and a mechanism, substantially 90 as described, for adjusting said arms vertically, in combination with the oscillating frame B and the driving mechanism, as described, a notched catch, M', vertically adjusted on the frame, a correspondingly-notched pawl, L', engaged by the catch M' during the oscillations of the frame B, a lever, K', fulcrumed between the arms C and to which the pawl is pivoted, a sliding plate, I, having a cutter or blade, I', secured thereto and engaged by the upper end 100 of the lever K', springs for retracting the plate I, and a spring and stop for returning the pawl to its normal position when released by the catch, substantially as herein described.

OLIVER B. REYNOLDS.
